UNITED STATES PATENT OFFICE

BERNDT JAKOB ERASMUS KROOK, OF STOCKHOLM, AND JOHANNES HÄRDÉN, OF LIDINGÖ, SWEDEN

AIRCRAFT

Application filed May 5, 1931, Serial No. 535,130, and in Sweden May 6, 1930.

When covering with fog, spreading of gases and the like from air-craft the following main points are very important. The apparatus should be light in proportion to the volume 5 of the gas supplying substance, which it is able to give off. The filling, transport and quick mounting of the apparatus on the air-craft should be easily effected. Further it should be securely controlled from the air-craft, even during aggravating circumstances occurring during the flying without unnecessarily encumbering the crew with extra labour. Moreover it should have such a form and such a location so as not to hinder the 10 movements of the air-craft. Finally the spreading member of the apparatus should be formed in such a way that the highest possible spreading effect is obtained without the ejected gases influencing either the crew or 15 the air-craft.

The present invention relates to such an apparatus for producing fog and spreading of gases from air-craft through which the above-mentioned requirements are filled, and 20 it is substantially characterized thereby that the fog or gas producing material is enclosed in a receptacle which is arranged outside the aircraft, preferably below the same so as to be pivoted or tilted, and from which 25 the fog-producing or gas-spreading material is ejected into the air through a spreading member.

An embodiment of the invention is illustrated in the accompanying drawings, in 30 which

Figure 1 is a side view of the apparatus, located on an aeroplane,

Figure 2 is a front view of the apparatus; and

Figures 3 and 4 show the spreading member seen from above and from behind respectively.

The apparatus consists substantially of a receptacle 1, preferably a metal cylinder, of a torpedo or streamline form. The receptacle 1 is by means of a pivot 2 located in a suspension device 3, so as to be turned or tilted, said suspension device being permanently secured between the landing and float-gauge 50 stay respectively. By pulling out the pivot

2 the receptacle is adapted to be detached and exchanged. The receptacle is balanced in such a way that its centre of gravity is located behind the shaft, and thus its narrower rear end, on account of the gravity, aims at moving downwards. It is held in its normal position by means of a thin wire-rope 4, which, over a block (not shown in the drawings) or the like proceeds up to the cabin of the pilot or to that of the observer.

During transport or under similar circumstances the receptacle is provided with a detachable protecting cap, quite covering the opening of the receptacle, said cap being unscrewed and the spreading member being substituted for same when the receptacle is pulled into its position.

The spreading member consists of a paddle shaped device 5, said device being, by means of a casing 6 provided with a screw-joint, adapted to be mounted on to the opening of the receptacle after the cap has been removed. A paddle-shaped shelter 7 to prevent the gases from being spread upward is located above the outlet opening. Between the paddles 5 and 7, said paddles increasing in width outwards counted from the opening, there are two curve-shaped side or partition walls 8—8 serving as deflection wings and diverging counted from said opening, whereby the lateral spreading is facilitated.

In the traverse passage of the spreading member said passage being located behind the opening of the receptacle, there is located a shutting off member (a lock-paddle or the like), which is adapted to be pulled out, and which is connected to the body of the aircraft by means of the wire-rope 9. When turning the rear portion of the receptacle downward about the pivot 2 by influence of the control line 4 the shutting off member is pulled out on account of the tension arising in the rope 9, by which the material producing the gas or fog is streaming out on the spreading member. The shutting off member can also be arranged automatically pivotable in the form of a valve or the like.

The spreading member is thus located that the air current, arising when the aircraft is in motion, sweeps past and under the edge

of the spreading member, whereby a whirl arises which increases the spreading. In order to obtain a further increased spreading effect the exhaust pipes from the engine may be extended under the lower edge of the spreading member, by which the whirls are increased by the influence of the exhaust gases.

According to the invention also other embodiments of the device than those described above may be thought of. The receptacle 1 can be thus arranged that the turning shaft of same takes up a position deviating more or less from the right angle to the longitudinal direction of the aircraft. The outlet opening might also be located on the side portion of the receptacle. Instead of using the ropes 4 and 9 stays, links or the like can be advantageously used.

The production or composition of materials intended for producing fog or gas are so well known within another line of the techniques, that they need not be more particularly described in this connection.

Having now described our invention, what we claim as new and desire to secure by Letters Patent is:

1. In an aircraft, a device for producing fog and spreading gases, comprising a receptacle for the taking up of the material producing the fog or the gas, said receptacle having an opening normally shut and being located outside the body of the aircraft and being pivotable in such a way that the contents can be ejected through the opening of the receptacle, and in which the normally shut opening of the receptacle is shut by means of a shutting member, which is automatically opened when the receptacle is turned.

2: In an aircraft, a device for producing fog and spreading gases, comprising a receptacle for the taking up of the material producing the fog or the gas, said receptacle having an opening normally shut and being located outside the body of the aircraft and being pivotable in such a way that the contents can be ejected through the opening of the receptacle, and in which the opening of the receptacle is provided with a shutting off member, which is connected to the body of the aircraft by means of a rope in such a manner that, when turning the receptacle, said shutting off member is opened by means of the tension arising in the rope.

3: In an aircraft, a device for producing fog and spreading gases, comprising a receptacle for taking up the material producing the fog or the gas, said receptacle being located outside the body of the aircraft and turnable and provided with an outlet opening, outside of which opening a spreading member is located, and in which the spreading member has the form of a downwards and backwards directed paddle-shaped de-

vice provided with curve shaped side-walls for taking up and spreading the ejected material producing the fog or gas, said walls diverging backwards and serving as deflection wings.

4. In an aircraft, a device for producing fog and spreading gases, comprising a receptacle for taking up the material producing the fog or the gas, said receptacle being located outside the body of the aircraft and turnable and provided with an outlet opening, outside of which opening a spreading member is located, and in which the spreading member is detachably mounted with respect to the opening of the receptacle and a protection cap to cover the outlet opening is provided to be substituted for the spreading member during transport.

5. In an aircraft, a device for producing fog and spreading gases, comprising a receptacle for taking up the material producing the fog or the gas, said receptacle being located outside the body of the aircraft and turnable and provided with an outlet opening, outside of which opening a spreading member is located, and in which a paddle-shaped shelter is located above the outlet opening, by which the gas is hindered from streaming upward.

In witness whereof we have hereunto signed our names.

BERNDT JAKOB ERASMUS KROOK.
